UNITED STATES PATENT OFFICE

157,665

TABLE SIRUP CONTAINER

Kenneth P. Duncan, Los Alamitos, Calif.

Application January 17, 1949, Serial No. 273

Term of patent 3½ years

(Cl. D58—8)

To all whom it may concern:

Be it known that I, Kenneth P. Duncan, a citizen of the United States of America, residing at Los Alamitos, in the county of Los Angeles and State of California, have invented a new, original, and ornamental Design for a Table Sirup Container, of which the following is a specification, reference being had to the accompanying drawing, forming part thereof.

Figure 1 is a perspective view of a table sirup container, showing my new design; Figure 2 is a side view of the container; and Figure 3 is an end view of same.

I claim:

The ornamental design for a table sirup container, as shown.

KENNETH P. DUNCAN.
